UNITED STATES PATENT OFFICE

BERT E. LANG, OF SPOKANE, WASHINGTON

TIRE-CHAIN LOCK

Application filed March 31, 1930. Serial No. 440,539.

This invention relates to a lock for an anti-skid chain, the general object of the invention being to provide means whereby the free end of each side chain of the anti-skid device is positively locked to the other end so that there is no danger of the parts becoming detached and there are no projecting parts to strike objects which might act to unfasten the device.

10 This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the device, showing the same in use.

Figure 2 is an edge view thereof.

Figure 3 is an edge view showing how a pointed member is used to unlock the device.

Figure 4 is an elevation with the pointed member in section.

Figure 5 is a longitudinal sectional view showing how the pointed member moves the inner part of the device to a position where it can be swung to unlocking position.

Figure 6 is a view similar to Figure 5, but showing the inner member in locking position.

Figure 7 is an elevation with the inner member swung outwardly and showing the pointed member used as a fulcrum for tightening the side chain.

Figure 8 is a perspective view of the outer member.

Figure 9 is a perspective view of the inner member.

Figure 10 is a view of the pointed member.

As shown in these views, the device comprises an outer member A and an inner member B, the outer member being of channel shape in cross section to receive the inner member. Said outer member has one

end enlarged, as shown at 1, with a rivet 2 passing through the enlargement and through the links 3 which are connected with the end link 4 of each side chain of the anti-skid device. The opposite end of the member A is formed with the hook 5 and in rear of said hook 5, each side part of the member A is formed with a small hook 6. The inner member B is formed with a hook at each end thereof, as shown at 7 and 8, and with a small hook 9 intermediate its ends, these hooks being connected with the same edge of the member. A curved slot 10 is formed in that end of the member B which carries the hook 7 and a rivet 11 in the hook 5 of the member A passes through this slot so that the member B is movably connected with the member A by this rivet. Thus the member B can pivot on the free end of the member A. The member B is swung inwardly into the member A, and with the rivet 11 engaging the outer end of the slot 10, the beak of the hook 8 can pass the rivet 2. Then by pushing the member B toward the hook 5, the rivet 11 will engage the inner end of the slot 10 and the hook 8 will engage the rivet 2 so that the parts are locked together and before they can be unlocked, the member B must be moved toward the link 4 in order to cause the hook 8 to clear the rivet 2. This is done by placing a pointed member 12 in the opening 13 formed by the hook 9 and the hooks 6, which forces the member B to the left in Figure 1. Then the member B has its hook 8 free of the rivet 2 so that it can be swung outwardly.

In fastening the ends of the side chain together, a link of the side chain is placed in the hook 8 of the member B after said member B is swung outwardly, as shown in Figure 7, and then after the chain is tightened, the link is placed in the hook 9. The member B is then swung toward the member A, which will cause the link to enter the hook 7 and finally the member B is pushed into the member A so that the link will be in engagement with both the hook 7 and the hook 5, as shown in Figure 1. The parts are then locked together by pushing the

member B toward the hook 5. When the device is to be opened, the pointed member is placed in the slot 13 so as to force the member B to the left in Figure 1, so that the member can then be swung outwardly to release the link of the side chain.

The member 12 is provided with a notch 13 which is adapted to be placed in engagement with the hook 8 so that the member 12 can act as a lever to facilitate the stretching of the side chain by the turning movement of the member B, as shown in Figure 7.

From the foregoing it will be seen that the device positively locks the ends of the side chain together so that there is no danger of the ends of the chain becoming separated and as the member B has its ends entirely enclosed by the member A, there are no projections for striking objects which might act to unlock the device and in order to unlock the device, the member B must be moved longitudinally with considerable force before it can be swung outwardly to release the link of the side chain.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A fastener for the ends of a side chain of a non-skid device, comprising a channel shaped member having one end enlarged and a hook at its other end, a rivet passing through the enlargement for connecting the member to one end of a side chain, an inner member having a hook at each end and a curved slot in one end, a pin passing through the slot and through the hooked portion of the channel shaped member, whereby the inner member is movably and pivotally connected with the hook end of the channel shaped member so that said inner member can be swung into the channel shaped member and then moved longitudinally to place one hook in engagement with the rivet, the second hook and the hook on the channel shaped member engaging a link at the other end of the side chain, means whereby a tool can be passed between the two members to move the inner member longitudinally to free its hook from the rivet, such means comprising a hook intermediate the ends of the inner member and hooks intermediate the ends of the outer member for forming a space to receive the tool when the parts are in closed position.

2. A fastener for the ends of a side chain of a non-skid device, comprising a channel shaped member having one end enlarged and a hook at its other end, a rivet passing through the enlargement for connecting the

member to one end of a side chain, an inner member having a hook at each end and a curved slot in one end, a pin passing through the slot and through the hooked portion of the channel shaped member, whereby the inner member is movably and pivotally connected with the hook end of the channel shaped member so that said inner member can be swung into the channel shaped member and then moved longitudinally to place one hook in engagement with the rivet, the second hook and the hook on the channel shaped member engaging a link at the other end of the side chain, means whereby a tool can be passed between the two members to move the inner member longitudinally to free its hook from the rivet, such means comprising a hook intermediate the ends of the inner member and hooks intermediate the ends of the outer member for forming a space to receive the tool when the parts are in closed position, said tool comprising a pointed member having a notch in one end thereof whereby said tool can be placed in engagement with the outer hook of the inner member to act as a lever for facilitating the tightening of the side chain.

In testimony whereof I affix my signature.

BERT E. LANG.
